RADIO CONTROL DEVICE

Carl H. Langley, Los Angeles, Calif., assignor of
forty-five per cent to Phillip K. Wiseman, Los
Angeles, Calif.

Application October 17, 1932, Serial No. 638,188

14 Claims. (Cl. 250—20)

My invention relates to a device for controlling the tuning mechanism of a radio set, such device being adapted to automatically change the adjusting or tuning of the radio at prescribed times so that pre-selected radio programs will be reproduced.

At the present time radio receiving sets are provided with one or more knobs whereby the tuning elements thereof may be adjusted for the reception of different wave lengths, thereby making it possible to receive or reproduce programs from any one of a large number of radio broadcasting stations.

It is an object of my invention to provide a device which may be pre-set so as to automatically produce a change in the adjustment of the tuning elements of the radio set at a prescribed time in the future to receive a selected broadcast wave and thereby reproduce the program of a selected station. The device is provided with a clock mechanism and a record member, or a plurality thereof, adapted to be pre-set or pre-adjusted to cover a future period of time, the timing means being associated with mechanism whereby the tuning element of a radio receiving set is readjusted in accordance with the manner in which the record or records have been pre-set. For example, radio programs are generally divided into minimum periods of time of fifteen minutes each, such periods starting on the four quarter divisions of each hour.

In the preferred practice of my invention I may provide a plurality of records, each representing a day of twenty-four hours divided into fifteen minute periods. In a simple manner this record may be pre-set or adjusted for each fifteen minute period, and as the record or control means is moved in fifteen minute intervals relative to the operating mechanism of my device, the record will control the operation of the mechanism in such a manner that the tuning element of the radio will be readjusted to tune the receiving set for the wave length, or radio station, indicated by the pre-setting or pre-adjustment of the record. Therefore by the use of my invention the radio receiving set may be automatically tuned or retuned at the beginning of each fifteen minute period throughout a number of days corresponding to the number of daily records in place in the controlling device.

It is an object of my invention to provide in a device of the above character a means for turning the tuning element shaft, or the tuning

dial, of a radio receiving set to a desired position, such means being capable of turning the dial either clockwise or counter-clockwise in accordance with the direction of rotation necessary to bring the dial into the predetermined position controlled by the setting of the record; and it is a further object to provide a means of this character which will adjust the tuning shaft or dial to relatively small divisions. For example, it is customary to divide the scale of the dial into one hundred units of movement or rotation of the tuning element which ordinarily is of condenser character. In my improved device the dial may be at a prescribed time in the future automatically rotated to any one of the unit divisions of the scale.

It is a further object of the invention to provide a device of the foregoing character which may be employed to automatically control the setting of a tuning unit of a radio but which may be manually disconnected at any desired time so that the radio may be manually tuned, but which device may be caused to automatically resume its function of automatically controlling at the end of a certain program or at some future time controlled by the records employed in the invention.

A further object of the invention is to provide a device of the above character in which the controlling records are moved at intervals across a prescribed position, and in which means are provided for holding the records in reserve and to move them in consecutive order relative to the operating mechanism, with the result that a continuous control of the radio receiving set may be accomplished through a period of time consisting of a number of days.

Further objects and advantages of the invention will be brought out in the following part of the specification.

Referring to the drawings, which are for illustrative purposes only,

Fig. 1 is a partly sectioned plan view of a preferred embodiment of my invention.

Fig. 2 is a cross sectional view taken substantially as indicated by the line 2—2 of Fig. 1.

Fig. 13 is a section similar to Fig. 12, showing the latch mechanism of Fig. 12 in position of engagement.

20 Fig. 14 is a wiring diagram for the electrical elements of the preceding illustrations.

Fig. 15 is a fragmentary elevational view looking at the leftward ends of the levers of the device as indicated by the arrow 15 of Fig. 1.

25 In Fig. 1 I show a housing or casing 15 preferably having parallel vertical side walls 16 and 17. By use of bearing members 18 a horizontal shaft 20 is supported between the side walls 16 and 17. Supported on this horizontal shaft are 30 a plurality of primary levers 21 and a plurality of secondary levers 22, the leftward ends of which are pulled horizontally upward by springs 23 connected to lugs 24 which extend leftwardly from a horizontal supporting structure 25 which has 35 its ends secured by means such as rivets 26 to the side walls 16 and 17 of the casing 15.

There are ten of the primary levers 21 and nine of the secondary levers 22, as clearly shown in Fig. 1. The rightward ends of the primary 40 levers 21, as shown in Fig. 7, have downwardly projecting brush members 27 having semi-spherical lower ends 28 and upwardly projecting stem portions 30 which extend into vertical openings 31 formed in the ends of the levers 21 and 45 being adapted to engage stationary contact blocks 32 to which conductors 33 may be secured.

As shown in Fig. 3, the rightward ends of the secondary levers 22 are provided with brush or contact members 34 which have relatively slender 50 points 35, the upper ends of which members 34 are adapted to engage stationary contact blocks 36 to which conductors 37 may be secured. Rightwardly of the shaft 20 a shaft 38 is extended horizontally between bearing members 55 48 carried by the side walls 16 and 17. As shown in Figs. 1 and 3, the portion of the shaft 38 adjacent the rightward ends of the secondary levers 22 has an upwardly extending blade or pawl 41 adapted to engage rightwardly extending dogs 60 or catches 42 on the ends of the secondary levers 22 to hold the levers 22 in raised position as shown in Fig. 3 until the proper time for release thereof. Extending leftwardly from the shaft 38 are arms 43 which support a horizontal bar 44 65 over the leftward portions of the primary levers 21.

As shown in Figs. 1 to 5, the horizontal supporting structure 25 has vertical holes 45 aligned with the rearward or leftward portions of the 70 primary and secondary levers 21 and 22, and in these vertical openings are primary and secondary pins 46 and 47, each of which has an upper end 48 of reduced diameter. The purpose of the pins 46 and 47 is to hold the leftward ends 75 of the levers 21 and 22 in lowered position and

to maintain the rightward ends of the levers 21 and 22 in raised position, as will be hereinafter explained. The holding down of a pin 46 or 47 will prevent the leftward end of the lever 21 or 22, with which it is associated, from being pulled upwardly by a spring 23.

To hold all or a selected number of the pins 46 or 47 downwardly, I provide a control or record member 50 of such character that it will provide one or more openings in the bottom thereof into which the upper reduced ends 48 of selected or predetermined pins 46 or 47 may upwardly extend, thereby permitting such pins to move upwardly and in turn permit the raising of the leftward ends of associated levers 21 and 22. 15

As shown in Figs. 2, 8, 9, 10, and 11, the record 50 in its preferred form comprises a flat plate 51 having consecutive rows of openings 52, 53, etc., disposed on lateral lines 54 and 55 which are preferably evenly spaced. Under each line 54, 55, or under each lateral row of holes, are aligned channels 56 and 57 which have blocks 58 longitudinally slidable therein. As shown in Fig. 9, the blocks 58 are of a length L shown equal to the spacing of the openings 52 and 53 along the lines 54 or 55 on which the openings are disposed, but the channels 56 and 57 are of such length that spaces 60 may be left at the ends of the channels adjacent the end block of each group of blocks 58 or so that by forcing a stylus or other slender member 61 downwardly through an opening 52 or 53, the blocks 58 may be forced apart to provide an opening 62 or 63 between adjacent blocks and under the opening 52 or 53 through which the slender member 61 has been passed as indicated in dotted lines 64 in Fig. 10. 30

The openings 52 are nine in number and are numbered in units, or from one to nine. The openings 53 are eleven in number, ten of them being numbered by tens from zero to ninety, and 40 the eleventh opening 53 being indicated by the word "Stop".

At the extreme ends of the channels 56 and 57 are holes 65 through which the stylus member 61 may be inserted so as to engage the ends of 45 the groups of blocks 58 so as to force the blocks into co-engagement and eliminate any opening 62 or 63 between the ends of the group of blocks in either channel 56 or 57.

The openings 52 and 53 are spaced along the 50 lateral lines 54, 55, at distances equal to the spacing of the parts 47 and 48. Accordingly, when a record 50 is in a position such as indicated in Fig. 2 with a cooperating pair of channels 56 and 57 aligned over the pins 46 and 47, the openings 55 62 and 63 formed between blocks 58 as previously described will be in position to receive the upper ends 48 of therewith aligned pins so as to permit upward movement of such pins and upward movement of the leftward ends of selected lever members 21 and 22 providing other conditions for such operation are proper. 60

In addition to the foregoing mechanism, the invention employs a clock 67 which is preferably of the synchronous motor driven type. From this clock 67 a shaft 68 extends which may revolve once every fifteen minutes, and on this shaft a rotating switch member 70 is mounted, such switch member having a radially extending contact 71 and a substantially circular insulating body 72. The shaft 68 has a driving lug 73 which projects into a segmental opening 74 in the member 70 for the purpose of rotating the member 70 in the direction of the arrow 75 by permitting 75

a limited forward movement of the member 70 on the shaft.

As shown in Figs. 4, 5, and 14, adjacent the member 70 is a stationary switch contact 76 which 5 is connected through a conductor 77 with a record advancing motor 78, this motor being connected with a conductor 80 which leads from a source of electrical power which may readily consist of a transformer 81. A conductor 82 is employed to connect the member 70 and its movable contact 71 with a second conductor 83 which extends from the transformer 81. The motor 78 is adapted to rotate a pinion 84, which in turn drives a gear 85 in clockwise direction as indicated 15 by the arrow 86 of Fig. 2. The face of the gear, 85 has a cam 87 thereon which is substantially circular with the exception of a flattened face 88 which faces downwardly when the cam is in a position of rest as shown in Fig. 2.

20 A lever 90 pivoted at 91 rests normally against the flattened face 88 of the cam 87, but as the cam 87 is rotated in clockwise direction through a position indicated by dotted lines 93, the lever 90 is swung downwardly to the position indicated 25 in dotted lines 94. As the cam 87 is further rotated in clockwise direction, a pin 95, which projects forwardly therefrom, engages a lever 96 which is rotatably mounted on a horizontal shaft 97. This lever 96 is accordingly swung into the 30 position indicated by dotted lines 98, and a pawl 100 thereon advances a ratchet wheel 101. The ratchet wheel 101 is non-rotatably secured to the shaft 97 so that rotation of the ratchet wheel 101 will produce rotation of the shaft 97 and 35 sprocket or pulley means 102 which are mounted thereon, an external knob 103 being provided whereby the shaft 97 may be manually rotated.

Over the pulley means 102 parallel belt means 104 and 105 are carried. These belt means pass 40 over pulley means 106 carried by a horizontal shaft 107, the upper portions of each of the members 104 and 105 passing over flat plates 108 which are carried near the ends of the horizontal supporting structure 25. The members 104 and 45 105 have outwardly extending engagement members 110 adapted to engage openings 111 in the lower edge portions of the record 50 whereby to propel the record 50 in forward direction as indicated by the arrow 112 of Fig. 2.

50 Each rotation of the pin 95 will produce an advance of the ratchet wheel 101 through an angular distance equal to one tooth, and such rotation of the ratchet wheel will produce a belt movement through the distance required to move 55 the record from one fifteen minute period to the next fifteen minute period, or from one cooperating pair of channels 56 and 57 to the adjacent channels 56 and 57 in the bottom of the record 50.

60 Means are provided for holding the leftward ends of all of the primary and secondary levers 21 and 22 in lowered positions, thereby assuring that all of the pins 46 and 47 will be in lowered position during the movement of the record 50 65 by the record advancing means previously described.

For moving the leftward ends of the levers 21 and 22 against the upward pull of the springs 23, I show vertical links 113 which are moved 70 downwardly in response to the downward movement of the lever 90 by the cam 87. Between the upper ends of the links 113 a bar 114 is extended, this bar passing over the leftward ends of the levers 21 and 22, with the result that with downward movement of the lever 90 there is produced 75

a downward movement of the bar 114 so as to move the leftward ends of all of the levers 21 and 22 downwardly.

In Fig. 4 the cam 87 and the pin 95, with their associated parts, are shown in their respective positions at the close of a record advancing movement. As the pin 95 travels downwardly from the position in which it is shown in Fig. 4, it releases the lever 96 and moves into engagement with the under side of a pin 120 which projects from the member 70 and lifts this pin 120 from the position in which it is shown in Fig. 4 into its position of Fig. 5, thereby rotating the member 70 on the shaft 68 and moving the contact 71 from engagement with the stationary contact 76, thereby cutting off the supply of electrical energy to the motor 78 so as to stop the cam 87 and its associated parts in a position of rest, the lever 90 being permitted at this time to swing upwardly into engagement with the flat face 88 of the cam 87 and release the levers 21 and 22 so that they will be drawn by the force of the springs 23 against the lower ends of the pins 46 and 47.

If the blocks 58 in a channel 57 lying above the pins 46 have been adjusted to provide a space or opening 63, the point 48 of the pin 46 aligned with such space or opening 63 will move upwardly into such space or opening 63 and permit a lever 21, such as specifically indicated at 21a in Fig. 2, to move downwardly from the raised position of Fig. 4, thereby bringing the brush or contact 28 at the rightward end of such lever 21a into engagement with a segmental contact 121 mounted on a drum 122.

It will be noted that at this time the pawl 41 holds the secondary levers 22 in raised position so that the leftward ends thereof are lowered. As shown in Fig. 15, the leftward end of each lever 22 carries a contact 123 adapted to engage stationary spring contact blades 124 which are 40 connected in series. The spring contact members may be supported on an insulated bar 125 carried by a supporting structure 126. As clearly shown in Fig. 14, all of the conductors 33 connected with the stationary contact blocks 32 at 45 the forward ends of the levers 21 are connected in multiple to a conductor 127 which connects to one end of the series of switch means 128 formed between contacts 123 and 124. The other end 50 128 of this series of switch means is connected through a conductor 130 with the feed conductor 80. Accordingly, when the lever indicated specifically at 21a in Fig. 2 drops into engagement with a segment 121, the brush 28 is lifted into engagement with its cooperating contact block 32, 55 thereby electrically connecting the segment 121 with the feed conductor 80.

As shown in Fig. 2, a second segment 131 is mounted on the drum 122 in alignment with the segment 121, but a space is provided between the 60 adjacent ends of the segments 121 and 131, this space being occupied by a body of insulating material 132 having a pocket 133 formed therein to receive the spherical lower end of the brush contact 28 carried by the lever 21a. The segment 121 is connected through a wire 134 with a ring 135, and the segment 131 is connected through a wire 136 with a ring 137, both of these rings being mounted at the end of the drum 122 so that brushes 140 and 141 may be supported in positions 65 70 to engage their respective rings 135 and 137.

By the use of wires 142 and 143, the respective brushes 140 and 141 are connected with motors 144 and 145, and these motors are connected through conductors 146 and 147 with the feed 75

conductor 33 as shown in Fig. 14. The motor 144 is provided with a pinion 148 engaging a gear 150 secured to the shaft 151 of the drum 122, and the motor 145 is provided with a pinion 153 which engages the gear 150. The motor 144 will rotate the drum 122 in clockwise direction, and the motor 145 will rotate the drum 122 in anti-clockwise direction.

As previously described, the dropping of the forward end of the lever 21a as shown in Fig. 2 has caused the contact 28 to engage the segment 121. From Fig. 14 it will be perceived that at this time the clockwise motor 144 will be energized by flow of current through the conductor 130, the switches 128, the conductor 127, the conductor 33 indicated specifically at 33a, the segment 121, a conductor 134, the ring 135, the brush 140, and the conductor 142. The operation of the motor 144 will cause the drum 122 to rotate in clockwise direction as viewed in Fig. 2, or rearwardly with relation to the tuning movement of the drum, and move the insulator 132 toward the brush contact 28, so as to carry the depression 133 into alignment with the contact 28, with the result that, as shown in Fig. 5, the brush contact will drop into the depression 133, thereby allowing the forward end of the lever 21a to swing downwardly. The corresponding upward movement of the leftward end of the lever 21a lifts the bar 44 and 30 swings the arms 43 upwardly, rotating the shaft 38 in clockwise direction and moving the pawl 41 from its position of engagement with the catches 42, as shown in Fig. 4, to a releasing position as shown in Fig. 5. At this time the springs 35 23 connected to the rearward ends of the levers 22 will pull upwardly on the rearward ends of the levers 22, forcing them against the pins 41. The opening 62 formed between the blocks 58 of the record 50, as shown in Fig. 10, will permit one 40 of the pins 47 to move upwardly, namely, the sixth pin indicated specifically at 47a. Accordingly, the lever 22 indicated at 22a may rotate in clockwise direction so as to move the brush contact 34 into engagement with a segment 154 45 mounted on the drum 122 in alignment with the lever 22a and raising the leftward end of the lever 22a so as to remove the contact member 123 at the leftward end thereof from engagement with the spring contact member 124 cooperating therewith. This opens the series of switch means 128 50 in the circuit leading to the clockwise motor 144, thereby de-energizing the motor through the electrical circuit which was originally closed by the dropping of the forward end of the lever 55 member 21a. As shown in Fig. 14, the conductors 37 connect the brush contacts 34 through the conductor 130 with the power feed circuit 80.

The segment 154 is connected through a wire 155 and a conductor 156 with the ring 135 in turn 60 connected to the motor 145. Accordingly, the anticlockwise motor 145 will be energized through the closing of a circuit resulting from the engagement of the brush contact 34 with the segment 154, and will rotate the drum 122 in anticlockwise or forward tuning direction until the point 35 of the brush contact 34 coincides with an approaching insulator body 158 in the segment 154.

It will be noted that the insulator member 158 70 has a depression or pocket 160 therein into which the point 35 may drop, thereby permitting the brush contact 34 to drop down from engagement with the contact block 36, breaking the circuit to the motor 144, and stopping the drum at the

point designated by the alignment of the pocket 160 with the point 35.

From the foregoing description it will be noted that the drum, in response to engagement of the contact 28 of the lever 21a with the segment 121, was first moved through a major distance, after which it was moved through a smaller distance in response to engagement of the contact 34 of the lever 22a with the segment 154. The drum may be connected through any suitable means, such as a shaft extension 163, with the tuning element of a radio set which has a rotating movement equal to an arc of rotation defined by the ends 164 and 165 of the segments 121 and 131, Fig. 2. The space 63, Fig. 10, which permitted the lowering of the rightward end of the lever 21a was produced by inserting the stylus member 61 through an opening 53 designated as 50 along the scale of 0 to 90 in Fig. 8.

The pocket 133, Fig. 2, formed in the insulator body 132 between the segments 121 and 131 is so positioned on the drum that the energization of the motor 144, through engagement of the contact 28 with the segment 121, causes the drum to move to a position half-way between the ends 164 and 165 of the arc of rotation so as to cause the tuning element of the radio set to be moved to a position "50" on a radio tuning scale divided into one hundred parts. The space 62, Fig. 10, which permitted the upward movement of the pin 47a and the downward movement of the rightward end of the lever 22a, is in a position corresponding to the numeral 5 along the leftward edge of the record 50 shown in Fig. 8. The pocket 160 in the insulator body 158, Fig. 3, is in a position five points to the right of the radial plane A—A of the pocket 133, with the result that the energization of the motor 144 through engagement of the brush contact 34 with the segment 154, has caused the drum to move 40 the tuning element of the radio set an additional five points beyond the "50" point or to a position at "55" on the tuning scale. Accordingly it will be seen that by inserting a stylus through the opening 53 opposite the position "50" designated at the leftward edge of the record 50 in Fig. 8, and through the opening 52 adjacent the numeral 5, the automatic tuning device has been controlled by the record in such a manner as to rotate the tuning element to the position 50 "55" on its scale at the beginning of a fifteen minute interval determined by the clock 67.

If at the beginning of the series of operations previously described, the drum 122 should be in such a position that the contact 28 of the lever 55 arm 21a drops into engagement with the segment 131, energization of the anti-clockwise motor 145 will result to turn the drum 122 in anti-clockwise direction to bring the pocket 133 into engagement with the brush contact 28, after 60 which the energization of the clockwise motor through closing of the circuit by engagement of the brush contact 34, Fig. 3, with the segment 154, will further move the drum to rotate the tuning element of the radio set to the "55" position on its tuning scale.

The ten levers 21 are representative of the ten major divisions of a tuning scale from one to one hundred, each of these major divisions consisting of ten units, and the nine levers 22 are 70 representative of nine unit divisions which may be disposed between any of the major divisions of the scale. Accordingly, each lever 21 is adapted to cooperate with segments similar to the segments 121 and 131, specifically designated as seg- 75

ments 121a and 131a, these segments, as illustrated in Fig. 14, being varied in length so that the insulator bodies 132a will assume positions on the drum corresponding to divisions of rotative movement zero, ten, twenty, thirty, forty, etc. Accordingly, insertion of a stylus member into any selected opening 53 designated by the scale zero to ninety on the record 50, Fig. 8, will select the lever 21 to engage the drum 122, and 10 such selected lever will cause the closing of a contact through either a segment 121a or a segment 131a to cause the movement of the drum into a position in accordance with the position of the opening 53 relative to the scale zero to 15 ninety on the record 50.

The levers 22 cooperate with the openings 52 along the scale one to nine of the record 50, and each of the levers 22 cooperates with a segment similar to the segment 154, which additional segments, shown in Figs. 1 and 14, are designated by the numeral 154a. Each of these segments 154 or 154a has ten of the insulator bodies 158 therein, and there are ten insulator bodies 132 and 132a cooperating with the segments 121, 131, 131a, and 121a. Each segment 154 or 154a therefore has an insulator body set slightly in advance of each insulator body 132 or 132a, the advance of the insulator bodies 154 and 154a relative to the insulator bodies 132 and 132a 30 corresponding to the numerical position of the segment 154 or 154a relative to the scale divisions one to nine. For example, in the explanation of the operation of the device, the insulator body 158, Fig. 3, was disposed six points or six units 35 beyond the plane A—A of the insulator body 132. The segment 154 has nine other insulator bodies 158a, each of which is disposed six points beyond a plane or position of an insulator body 132. Therefore, should any one of the levers 21 be selected to produce movement of a corresponding 40 insulator body 132 or 132a into the vertical plane B—B in which the contacts 28 are disposed, the segment 154 will have a contact body 158 or 158a disposed six points therebeyond, and each of the 45 remaining segments 154a will provide insulator bodies 158a disposed beyond the position at which the drum has stopped in accordance with the numerical value of the segments 154 or 154a. It is therefore possible by adjustment of the blocks 50 50 of the record 50 to automatically control the movement of the drum 122 into any selected unit division between the points zero and one hundred, thereby making it possible to pre-set the record 50 so that the radio set will be adjusted 55 to receive any desired wave length at a prescribed time in the future.

It will be noted that the record 50 is provided with adjacent rows of openings 52 and 53 throughout the length thereof on lateral lines 60 54 and 55. These rows of holes are spaced apart distances corresponding to one advancing movement of the record by the advancing mechanism controlled by the clock, and accordingly the rows of holes may be numbered for fifteen minute intervals as at 175 along one edge of the record, and the records may be of any desired length, such as twenty-four hours.

The invention further comprehends the use of a plurality of records, indicated individually at 70 50a in Fig. 2, which records may be stacked in a suitable guide or receiver 176 so that they will drop into position for engagement by projections 110 as each preceding record is carried out from under the stack of records. Therefore, if the records are made of such length that each will con-

trol a twenty-four hour period, an entire week's program may be arranged by use of a stack of seven records. By inserting the stylus through any of the holes 53 aligned with the designation "Stop", the mechanism may be controlled to shut off the radio during one or more fifteen minute periods. A pin 178, Figs. 1 and 6, is positioned over the row of "Stop" openings of the record, and the lower end thereof is adapted to control the movement of a switch lever 180 which extends leftwardly from the shaft 29. On a pivot 181a switch member 182 is swingably mounted in such position that its rearward end 183 will be engaged by the leftward or rearward end 184 of the lever 180 when the pin 178 is permitted to move upwardly by the record 50 so that the lever 180 may be swung into the dotted line position 185. The resulting swinging movement of the switch member 182 causes a knife switch 186 to be opened, thereby breaking the radio feed circuit so that the radio set will not play, but without interfering with the intermittent advancing of the record 50 as previously described.

The wiring diagram of Fig. 14 shows the switch 186 in a circuit 190 adapted to connect the radio set with a 110-volt service wiring 191. A manual radio control switch 192 is shown in a position to bridge across the switch 186 so that the radio set may be turned on manually should the switch 186 be opened in response to a setting of the record 50, thereby making it possible to turn the radio set on at any time during such periods as the setting of a record may maintain it in inoperative condition. The record accordingly may be set to stop the radio set and maintain it in an off condition through any desired period of time and to turn the set on and off at various times. The bar 44 has a projecting end which extends under the rightward portion 193 of the switch member 182 which will operate to close the switch 186 whenever a lever member 21 is caused or permitted to rotate in clockwise direction as a result of the dropping of a brush contact 28 into a recess or pocket 133, thereby re-energizing the radio set whenever the blocks 58 of the record 50 are in position to produce an operation of the drum 122.

The automatic tuning device may be rendered temporarily inoperative by use of a knob 195 which is mounted on a shaft 196 extending 50 through a case 197, Fig. 1. As shown in Fig. 12, this shaft 196 is normally rotated by a spring 198 in anti-clockwise direction to bring a projection 200 extending from a disc 201 mounted on the shaft 196 against a stop 202. The shaft extends horizontally under the rightward ends of the levers 21 and 22 and has a cam 203 thereon, as shown in Figs. 2 and 3, this cam having a shoulder 204 thereon adapted to engage a notch 205 in one of the levers 21 or 22 when the cam is rotated into raised position to lift the rightward ends of all of the levers. Accordingly, should it be desired to change the setting of the drum and of the tuning dial of the radio set at any time, the knob 195 may be rotated against the action 65 of the spring 198 through an angle of 180° so as to lift the levers 21 and 22 from the possibility of their engagement with the segments carried by the drum 122. The engagement of the shoulder or ratchet 204 with the notch 205 will prevent the cam from rotating to its normal lowered position until the subsequent operation of the cam 87. Accordingly, at the end of the fifteen minute period during which the cam 203 has been actuated, the lever 90 will be forced 70 75

downwardly, and the bar 114 will raise the rightward ends of the levers 21 and 22, thereby removing the notch 205 from engagement with the shoulder 204, allowing the spring to rotate the 5 shaft 196 and carry the cam 203 into lowered position.

The foregoing manner of manipulating the knob 195 makes it possible to change the tuning of the radio set during a fifteen minute period 10 but permits the automatic tuning device to resume its control of the radio tuning element at the end of the fifteen minute period. Means are also provided whereby the levers 21 and 22 may be held in a raised position for an indefinite 15 period. Such means consists of a pawl 206 mounted within the case 197 and being adapted to engage a shoulder 207 carried by the disc 201. The pawl 206 is normally held in outward position by a light spring 208 which will permit 20 movement of the pawl, by a manually operable pin or plunger 210, from the position in which it is shown in Fig. 12 to the position of engagement with the shoulder 207, as shown in Fig. 13. The force of the shoulder against the pawl 206 25 holds these parts in engagement against the pressure of the spring 208 until the knob 195 is manually rotated in clockwise direction to disengage the shoulder 207 from the pawl 206. Accordingly, the cam 203 may be latched in raised 30 position and may be subsequently released by merely turning the knob 195 to disengage the catch formed by the pawl 206 and the shoulder 207.

The operation of the radio control device when 35 there is no record present in position to cooperate with the pins 46 and 47 is prevented by a latch consisting of a bar 212 pivoted at 213 having a laterally extending arm 214 adapted to extend upwardly into the path of the record 40 50, and when the member 212 is pulled leftwardly by a spring 215, the lower end of the member 212 engages the bar 44 so as to prevent upward movement of this bar 44 when no record is in operative position. The moving of the record 45 50 into operative position as shown in Fig. 2 depresses the upwardly extending portion 214 and causes the member 212 to swing from dotted line position to full line position of Fig. 2, thereby releasing the bar 44 so that the leftward portions 55 of the levers 21 may swing upwardly and so that upward movement of the extending end of the bar 44 may close the switch 186.

Although I have herein shown and described my invention in simple and practical form, it is 55 recognized that certain parts or elements thereof are representative of other parts, elements, or mechanisms which may be employed in substantially the same manner to accomplish substantially the same results; therefore, it is to be understood that the invention is not to be limited to the details disclosed herein but is to be accorded the full scope of the following claims.

I claim as my invention:

1. A device of the character described for 60 automatically adjusting a member in accordance with a predetermined schedule, including: a record having consecutive groups of adjustable parts thereon, there being means whereby said parts may be adjusted to positions representative of desired positions of said member to be adjusted; means for producing a movement of said record to bring said groups of adjustable parts individually into a plane of operation; and actuating means controlled by the group of said adjustable 65 parts in said plane of operation for moving said

member to the position represented by said adjustable parts.

2. A device as defined in claim 1, in which said record comprises a body having consecutive guides, and said adjustable parts consist of relatively small block members slidable in said guides. 5

3. A device as defined in claim 1 in which said record comprises a body having consecutive guides, and said adjustable parts consist of relatively small block members slidable in said guides, there being openings in said body for guiding a stylus-like member into engagement with said block members. 10

4. A device as defined in claim 1 in which said record comprises a flat body having parallel channels in the bottom thereof and said adjustable parts comprise blocks slidably disposed in said channels, there being openings extending from the top of said body into said channels for guiding block-moving means into engagement with said blocks to move them into desired positions of adjustment. 15

5. A device as defined in claim 1 in which said record comprises a flat body having parallel channels in the bottom thereof and said adjustable parts comprise blocks slidably disposed in said channels, there being openings extending from the top of said body into said channels for guiding block-moving means into engagement with said blocks to move them into desired positions of adjustment, there being characters on 20 said body in cooperation with said openings, indicative of the positions to which said first named member may be moved by said actuating means 30 under control of said record. 35

6. A device of the character described for automatically adjusting a member in accordance with a predetermined schedule, including: a record having consecutive groups of adjustable parts 40 thereon, there being means whereby said parts may be adjusted to positions representative of desired positions of said member to be adjusted; means for producing a movement of said record to bring said groups of adjustable parts individually into a plane of operation; actuating means controlled by the group of said adjustable parts in said plane of operation for moving said member to the position represented by said adjustable parts; and means selectively actuatable to prevent operation of said actuating means without interfering with the movement of said record. 45

7. A device of the character described for automatically adjusting the tuning element of a 50 radio receiving set in accordance with a predetermined schedule, including: a record having consecutive control parts thereon; means for moving said record to bring said control parts consecutively into a plane of operation; and actuating means controlled by said control parts in said plane of operation for moving said tuning element to positions in accordance with the characteristics of said control parts of said record, said actuating means comprising a movable part 55 connected to said tuning element, engagement members controlled by said control parts of said record to move between inoperative and operative positions relative to said movable part, means for moving said movable part in response to the 60 movement of an engagement member into operative position, and a plurality of stop means on said movable part in positions corresponding to the positions to which said tuning element may be adjusted for cooperation with said engage- 65

ment members and stopping said movable part in consequence of the engagement of an engagement member in operative position with its co-operating stop means.

5 8. A device of the character described for automatically adjusting the tuning element of a radio receiving set in accordance with a predetermined schedule, including: a record having consecutive control parts thereon; means for 10 moving said record to bring said control parts consecutively into a plane of operation; and actuating means controlled by said control parts in said plane of operation for moving said tuning element to positions in accordance with the 15 characteristics of said control parts of said record, said actuating means comprising a rotatable drum connected to said tuning element, engagement members controlled by said control parts of said record to move between inoperative and 20 operative positions relative to said rotatable drum, means for rotating said drum in consequence of the movement of an engagement member into operative position, and a plurality of stop means on said drum in positions corresponding 25 to the positions to which said tuning element may be adjusted for cooperation with said engagement members and stopping said drum in consequence of the engagement of an engagement member in operative position with its co-operating stop means.

30 9. A device of the character described for automatically adjusting the tuning element of a radio receiving set in accordance with a predetermined schedule, including: a record having consecutive control parts thereon; means for 35 moving said record to bring said control parts consecutively into a plane of operation; and actuating means controlled by said control parts in said plane of operation for moving said tuning element to positions in accordance with the characteristics of said control parts of said record, said actuating means comprising a movable part connected to said tuning element, engagement members controlled by said control parts of said 40 record to move between operative and inoperative positions relative to said movable part, a plurality of stop means cooperative with said engagement members, said stop means being disposed in adjacent paths on said movable part traversed by 45 said respective engagement members, contact plates on opposite sides of said stop means in said paths, and contacts carried by said engagement members adapted to respectively engage contact plates in said paths when said engagement members are moved into operative position, said contact plates and said contacts being connected to said electrical drive means so as to energize said electrical drive means in a manner to produce movement of said movable part in a direction to carry a cooperating stop means toward an engagement member which has 50 been moved into operative position of control of said record.

55 10. A device of the character described for automatically adjusting the tuning element of a radio receiving set in accordance with a predetermined schedule, including: a record having consecutive control parts thereon; means for 60 moving said record to bring said control parts consecutively into a plane of operation; and actuating means controlled by said control parts in said plane of operation for moving said tuning element to positions in accordance with the characteristics of said control parts of said record, 65 said actuating means comprising a movable part connected to said tuning element, electrical drive means for moving said movable part forwardly or rearwardly, engagement members controlled by said control parts of said record to move between operative and inoperative positions 70 relative to said movable part, a plurality of stop means formed of insulating material on said movable part cooperative with said engagement members, said stop means being disposed in adjacent paths traversed by said respective engagement members, contact plates on opposite 75

said movable part, a plurality of stop means cooperative with said engagement members, said stop means being disposed in adjacent paths on said movable part traversed by said respective engagement members, and switch means on opposite sides of said stop means operative, upon engagement with an engagement member in operative position, to cause said electrical drive means to move said movable part in a direction to produce engagement of the engagement member in operative position, with its co-operating stop means, said stop means being adapted to discontinue the operation of said electrical drive means in consequence of the engagement of said stop means with its co-operating engagement member.

15 11. A device of the character described for automatically adjusting the tuning element of a radio receiving set in accordance with a predetermined schedule, including: a record having consecutive control parts thereon; means for 20 moving said record to bring said control parts consecutively into a plane of operation; and actuating means controlled by said control parts in said plane of operation for moving said tuning element to positions in accordance with the characteristics of said control parts of said record, said actuating means comprising a movable part connected to said tuning element, electrical drive means for moving said movable part forwardly or rearwardly, engagement members controlled by said control parts of said record to move between operative and inoperative positions relative to said movable part, a plurality of 25 stop means cooperative with said engagement members, said stop means being disposed in adjacent paths on said movable part traversed by said respective engagement members, contact plates on opposite sides of said stop means in said paths, and contacts carried by said engagement members adapted to respectively engage contact plates in said paths when said engagement members are moved into operative position, said contact plates and said contacts being connected to said electrical drive means so as to energize said electrical drive means in a manner to produce movement of said movable part in a direction to carry a cooperating stop means toward an engagement member which has 30 been moved into operative position of control of said record.

35 12. A device of the character described for automatically adjusting the tuning element of a radio receiving set in accordance with a predetermined schedule, including: a record having consecutive control parts thereon; means for 40 moving said record to bring said control parts consecutively into a plane of operation; and actuating means controlled by said control parts in said plane of operation for moving said tuning element to positions in accordance with the characteristics of said control parts of said record, said actuating means comprising a movable part connected to said tuning element, electrical drive means for moving said movable part forwardly or rearwardly, engagement members controlled by said control parts of said record to move between operative and inoperative positions relative to said movable part, a plurality of stop means formed of insulating material on said movable part cooperative with said engagement members, said stop means being disposed in adjacent paths traversed by said respective engagement members, contact plates on opposite 45

sides of said stop means in said paths, and contacts carried by said engagement members adapted to respectively engage contact plates in said paths when said engagement members are moved into operative position, said contact plates and said contacts being connected to said electrical drive means so as to energize said electrical drive means in a manner to produce movement of said movable part in a direction to carry a co-operating stop means toward an engagement member which has been moved into operative position under control of said record, the engagement of such stop means with such engagement member interrupting the flow of electrical energy to said electrical drive means.

13. A device of the character described for automatically adjusting the tuning element of a radio receiving set in accordance with a predetermined schedule, including: a movable part adapted to be connected with said tuning element, said movable part having primary and secondary paths of movement defined thereon; a primary stop means disposed in each of said primary paths of movement and being spaced at major intervals relative to the direction of movement of said movable part; a secondary stop means in said secondary paths of movement, said secondary stop means being spaced, in the direction of movement of said movable part, at minor intervals designating divisions of said major intervals; a primary engagement member for each of said primary paths of movement adapted to be selectively moved to engage said primary paths of movement; a secondary engagement member for each of said secondary paths of movement adapted to be selectively moved to engage said secondary paths of movement; electrically actuated drive means for moving said movable part forwardly or rearwardly; primary control means associated with said primary paths of movement operative on engagement of a selected primary engagement member with its cooperating primary path to cause said drive means to move said movable part in a direction to bring the primary stop means in said cooperating primary path into engagement with said selected primary engagement member; and secondary control means associated with said secondary paths of movement, operative on engagement of a selected secondary engagement member with its cooperating secondary path to cause said drive means to move said movable part to bring the said secondary stop means in said cooperating secondary path into engage-

ment with said selected secondary engagement member, whereby said movable part will be stopped at a position offset from its position wherein said primary engagement member engaged its cooperating primary stop means.

14. A device of the character described for automatically adjusting the tuning element of a radio receiving set in accordance with a predetermined schedule, including: a movable part adapted to be connected with said tuning element, said movable part having primary and secondary paths of movement defined thereon; a primary stop means disposed in each of said primary paths of movement and being spaced at major intervals relative to the direction of movement of said movable part; a secondary stop means in said secondary paths of movement, said secondary stop means being spaced, in the direction of movement of said movable part, at minor intervals designating divisions of said major intervals; a primary engagement member for each of said primary paths of movement adapted to be selectively moved to engage said primary paths of movement; a secondary engagement member for each of said secondary paths of movement adapted to be selectively moved to engage said secondary paths of movement; electrically actuated drive means for moving said movable part forwardly or rearwardly; primary switch means for controlling the flow of electric energy to said drive means operative on engagement of a selected primary engagement member with its cooperating primary path to cause said drive means to move said movable part in a direction to bring the primary stop means in said cooperating primary path into engagement with said selected primary engagement member, such engagement opening said stop means and stopping said drive means; secondary switch means for controlling the flow of electric energy to said drive means, operative on engagement of a selected secondary engagement member with its cooperating secondary path to cause said drive means to move said movable part to bring the said secondary stop means in said cooperating secondary path into engagement with said selected secondary engagement member, whereby said secondary switch means is opened and said movable part is stopped at a position offset from its position wherein said primary engagement member engaged its cooperating primary stop means.

CARL H. LANGLEY.
